UNITED STATES PATENT OFFICE.

WILLIAM HENRY JAY, OF MOBRIDGE, SOUTH DAKOTA.

COMBINATION-LOCK.

1,313,536.

Specification of Letters Patent.

Patented Aug. 19, 1919.

Application filed May 21, 1919. Serial No. 298,602.

To all whom it may concern:

Be it known that I, WILLIAM HENRY JAY, a citizen of the United States, and a resident of Mobridge, in the county of Walworth and State of South Dakota, have invented certain new and useful Improvements in Combination-Locks, of which the following is a specification.

My present invention relates generally to combination locks and more particularly to a combination lock for doors and other places, more especially those employing a bolt throwing member actuated by the door knob, and my primary object is the provision of a simple, inexpensive device of this type capable of manual control and in which the necessity of carrying the key is avoided, thus rendering the device particularly desirable in hotels and the like.

With the above statement generally in mind, my invention resides more particularly in the features of construction, arrangement and operation to be now described with respect to the accompanying drawing, forming a part of this specification, and wherein:

Figure 1 is a perspective view of the invention as applied to a door, looking from the outside,

Fig. 2 is a vertical transverse section, Fig. 3 is a detail perspective view of one of the tumbler actuating members removed, Fig. 4 is a detail perspective view of the knob carried key and its connecting part removed, and

Fig. 5 is a face view of one of the tumblers.

Referring now to these figures, my invention is embodied within a casing 15 which as seen in Fig. 1 in particular, is attachable to a door or other part to be locked, as indicated at 16, and securely fastened in connection therewith by any suitable means as, for instance, bolts 17, the outer face of the said casing 15 having a dial 18 around the outer edge of a circular slot 19, the purpose of which will be presently described. At the lower central portion of the casing 15, and secured upon the outer face or wall thereof, is a vertically disposed door knob supporting member 20 which bridges the lower portion of the slot 19 and the upper end of which is apertured to rotatably receive the inner reduced portion of a hollow knob 21, the aperture of the knob supporting member 20 being in line with front and rear aper-

tures 22 and 23 of the casing 15 for the reception of a lengthwise movable connecting bar 24 movable to engage and disengage its inner end with respect to the bolt throwing member generally indicated at 25 in Fig. 2, with which the adjacent portion 26 of the inner door knob (not shown) is connected as usual.

The connecting bar, which as above stated is shiftable lengthwise through the openings 22 and 23 of the casing and into and out of engagement with the bolt throwing member 25, is pivotally connected at 27 at its forward end, to the inner end of the knob 21 carried key 28, the outer end of the latter projecting externally through a slotted opening 29 formed in the outer face of the door knob, and the configuration of which prevents complete withdrawal of the key 28 with the connecting bar 24, the latter being prevented from passing through the slot 29. In this way, the key for moving the bolt is, in its various positions of lengthwise adjustment, constrained to rotation with the knob 21 by virtue of its extension through the slotted opening 29 and it is obvious that when the key is shifted inwardly, as seen in Fig. 2, turning movement of the knob 21 is communicated through the key and through the connecting bar 24 to the bolt throwing member 25.

Means are provided in connection with the casing, however, for normally preventing inward shifting movement of the connecting bar 24 through the casing 15, and these means comprise a pair of tumbler disks 30 and 31 mounted in spaced relation and independently rotatable upon a shaft or bolt 32 which is mounted through the casing 15 parallel with and above the connecting bar 24. Mounted also upon the shaft or bolt 32 are a pair of tumbler actuating members, one of which is seen in detail in Fig. 3, each of these members including a disk 33, rotatable by virtue of the central opening 34, upon the shaft or bolt 32, and to which one end of a manual controlling arm 35 is connected at 36. This controlling arm 35 is intermediately bent at an angle as indicated at 37, so as to extend forwardly through the slot 19 of the casing 15, its offset extremity 38 having a pointer 39 movable on the dial 18 of the casing and provided with a small stud 40 forming a handle. Each of the disks 33 is rotatably connected to its respective tumbler disk 30, 31 by the interposition of a

friction disk 41 therebetween, these two friction disks 41 being either of special friction material or, for instance, roughened metal so as to grip the adjacent faces of the disk 33 5 and the disks 30 and 31. Moreover, each tumbler disk 30, 31 and its respective disk 33 are separated from the other pair of disks and from the side walls of the casing by smooth-faced washers 42, so that when one 10 of the tumbler disks is rotated, communication of rotation to the other tumbler disk is thereby avoided.

In order that the disks 33 may be firmly connected to their respective tumbler disks 30 and 31, the bolt or shaft 32 is threaded 15 at one end, adjacent to the knob 21, for the reception of a wing nut 43 and the like, by rotation of which in one direction, the several disks of the series on the shaft or bolt 20 are clamped to one another.

Each of the tumbler disks, one of which is shown in detail in Fig. 5, has an annular series of small openings 44 and a single larger opening 45 the latter of which is of 25 sufficient diameter to receive the connecting bar 24. In this way, when the handle of each of the controlling arms 35 is grasped in turn and the arm shifted to the required number on the dial, the enlarged openings 45 of the 30 two tumbler disks will be alined with the openings 22 and 23 and the inner and outer walls of the casing may then be raised to the position shown in Fig. 1 and shifted inwardly, pushing the connecting bar 35 through the several alined openings and into engagement with the bolt throwing member 25.

By virtue of the possibility of movement between the controlling arms 35 and the tumbler disks 30 and 31, it is obvious that 40 when the connecting bar 24 is in the position shown in Fig. 2, that is, in its engaged relation and extending through the several alined openings 22, 45 and 23, the wing nut 43 of the bolt or shaft 32 may be loosened, permitting relative movement of the controlling arms with their disks 33, in respect 45 to the tumbler disks, and enabling the operator to set the controlling arm to the desired point on the scale which will thereafter 50 become the combination numbers when the wing nut 43 has again been tightened to clamp the disks 33 into engagement with their respective tumbler disks through the friction disks 41.

It will also be seen by reference to Fig. 4 that the inner end of the connecting bar 24 has reduced extensions 46 so that coöperation is thus had with the annular series of 60 small openings 44 and the tumbler disks in order to prevent unwarranted tampering with the lock, and obviate the possibility of shifting the inner end of the connecting bar against either of the disks, and then simply 65 rotating the latter until, with pressure

against the connecting bar, it slips through the opening as the latter comes into register.

It is obvious, furthermore, that my invention thus provides a simple, inexpensive construction, whereby the necessity of carrying 70 a door key is eliminated, rendering the invention particularly desirable in connection with hotel use, especially in view of the fact that the combination may be changed readily and quickly. 75

It is also to be observed and borne in mind that the combination parts as herein described and illustrated may be adopted to other forms of locks and latches beyond those noted above. 80

I claim:—

1. In a lock of the character described, the combination of a bolt throwing member, a knob or handle normally rotatable freely with respect to said member, a connecting 85 bar shiftable lengthwise into and out of engagement with the bolt throwing member, a key connected to one end of the connecting bar and extending through a slotted opening in the knob or handle, a casing in connection with which the knob or handle is mounted to rotate, having openings therethrough in which the connecting bar is movable, and provided with a dial, a shaft extending through the casing, tumbler disks 90 rotatable on the shaft and extending into the path of movement of the connecting bar, each of said disks being provided with an opening arranged for alinement with the connecting bar receiving openings of the 100 casing, and a controlling arm having connection with tumbler disks and provided with a portion extending exteriorly of the casing and overlying the dial thereof.

2. In a lock of the character described, the 105 combination of a bolt throwing member, a knob or handle normally rotatable freely with respect to said member, a casing in connection with which the knob or handle is rotatable, a connecting member shiftable 110 lengthwise through the casing and into engagement with the said bolt throwing member, a key having a slidale non-rotatable connection with the knob or handle and also having connection with the said connecting 115 member, and means within the casing to normally prevent lengthwise movement of the connecting member, including a pair of rotatable tumbler disks, each having an opening for alinement with the connecting 120 member, and an externally projecting manual controlling arm for each of the said tumbler disks, as described.

3. In a lock of the character described, the combination of a bolt throwing member, 125 a knob or handle normally rotatable freely with respect to said member, a connecting member shiftable through the knob or handle and having a non-rotatable connection therewith and movement with respect there- 130

to, into and out of engagement with the bolt throwing member, rotating tumblers in the path of movement of said connecting member and having openings through which the 5 said member is movable, and manual connections for rotating said tumblers.

4. In a lock of the character described, the combination of a bolt throwing member, a knob or handle normally rotatable freely 10 with respect to said member, a connecting member shiftable through the knob or handle and having a non-rotatable connection therewith and movement with respect thereto, into and out of engagement with the bolt 15 throwing member, rotating tumblers in the path of movement of said connecting member and having openings through which the said member is movable, and manual connections for rotating said tumblers, said 20 last named connections including manual controlling arms, and controlling disks adjacent to the tumblers and from which the said arms extend, having detachable engagement with the tumblers, as described.
5. In a lock of the character described, the combination of a bolt throwing member, a knob or handle normally rotatable freely with respect to said member, a connecting member shiftable through the knob 25 or handle and having a non-rotatable connection therewith and movement with respect thereto, into and out of engagement with the bolt throwing member, rotating tumblers in the path of movement of said 30

connecting member and having openings 35 through which the said member is movable, manual operating connections movable with respect to said tumblers, and means for normally clamping said manually operating connections in engagement with the tum- 40 blers.

6. In a lock of the character described, the combination of a bolt throwing member, a knob or handle normally rotatable freely with respect to said member, a connecting 45 member having a sliding non-rotatable connection with the knob or handle and movable with respect thereto into and out of engagement with the bolt throwing member, a casing through which the said connecting member is movable, a shaft in the casing parallel to the connecting member, tumbler disks rotatably disposed upon the said shaft and having openings movable into alignment with one another and the said 50 connecting member, manual controlling means for moving the tumbler disks, including disks also rotatable on the shaft, and controlling arms extending exteriorly of the casing from the last mentioned disks, friction disks disposed between the said controlling arm disks and the tumbler disks, said shaft having one threaded end, and a 55 wing nut threaded on the shaft to clamp the disks of each pair in connection with one 60 another.

WILLIAM HENRY JAY.
